United States Patent Office.

J. F. TROXEL, OF BLOOMSVILLE, OHIO.

Letters Patent No. 72,123, dated December 10, 1867.

IMPROVEMENT IN STEAM-ENGINES.

The Schedule referred to in these Letters Patent and making part of the same.

TO ALL WHOM IT MAY CONCERN:

Be it known that I, J. F. TROXEL, of Bloomsburg, in the county of Seneca, and State of Ohio, have invented a new and useful Improvement in Steam-Engines; and I do hereby declare that the following is a full, clear, and exact description thereof, which will enable others skilled in the art to make and use the same, reference being had to the accompanying drawings forming part of this specification.

This invention relates to a new and improved construction of steam-engines, whereby the same are greatly increased in power and effectiveness; and the invention consists in the arrangement of several pistons in one cylinder, and in the construction and arrangement of the parts, as will be hereinafter more fully described.

Figure 1 is a vertical longitudinal section of the engine through the line $z z$ of fig. 2, showing the cylinder and the pistons therein, and the manner in which the piston-rods are connected with the main shaft.

Figure 2 is a horizontal longitudinal section of the engine, showing, also, a top or plan view of the connecting-rods, main shaft, and valve-movement.

Figures 3 and 4 are detached views of the cylinder, showing the steam-ports and steam-valve, with the pistons represented in different positions in the cylinder, or as taking steam from the different ports.

Similar letters of reference indicate corresponding parts.

A represents the cylinder. C, D, and E represent the pistons. The principal feature of my invention is operating pistons in a cylinder without heads, and thereby exerting the full expansive force of the steam upon the main shafts. Two of these pistons, C and E, are connected with a bar, F, which slides by the side of the cylinder (outside.) G and H are arms, attached to the bar F. To these arms the rods are attached upon which are fixed the pistons C and E, as seen in the drawing. J is the rod for the piston C, and K for the piston E. The piston D is attached to another rod, L. These rods are attached to a double crank, m, on the end of the main shaft, by connecting-rods or pitman n and o. The piston-rod K is in the form of a half tube or a semicircle, and the piston-rod L is partially enclosed by it, which enables it to pass through and work in the centre of the piston E. P P' represent the steam-ports. R is the exhaust-port, and S is the induction-port. Referring again to the pistons, the arrangement is such that as the shaft revolves, the pistons D and C, and D and E, are moved in opposite directions, and approach each other when opposite the ports, as seen in the figs. 3 and 4, and when thus opposite, the cylinder is taking steam between the two pistons C and D, fig. 3, and exhausting it between the pistons D and E. In fig. 4 the position of the pistons is reversed. There the steam is entering the cylinder between the pistons D and E from the port P', and exhausting it from between the pistons C and D, through the port P. The effect of the steam is to force the pistons D E from each other, and the whole of the moving-power thus imparted is exerted directly on the main shaft through the double crank m. Attached to two of the pistons, C and D, as seen in fig. 1, are springs f f, which are so planed that as the pistons approach each other, as seen in figs. 3 and 4, the tendency of the spring is to assist the steam in starting or reversing the motion. T is the valve, which in this arrangement is a very simple and ingenious device for changing the steam from one port to the other, as is indicated by the arrows. u is a rod, which is attached to this valve, which rod is supported by a stand or bearing at its outer end, as seen in the drawing. To operate the valve T, or to give it an oscillating motion, which is the motion required for opening and closing the ports or steam-apertures, there is an arm, V, on the piston-rod K. w w are tappet-pins on the valve-rod u, which are placed at a proper distance from each other.

It will be seen that as the arm V is moved back and forth by the piston-rod, to which it is attached, it will strike the tappet-pins and move the valve-rod u, and consequently oscillate the valve, thus changing the steam from one port to the other alternately, and thereby allowing the steam to exhaust at the same time. The power derived from the expansive force of steam in forcing asunder pistons in a cylinder, according to my invention, may be applied to every description of machinery driven by steam, with the proper variations in the details to adapt the engine to particular circumstances and situations.

In applying the engine to locomotives, the main shaft would represent the axle, and the pitman n o would be connected directly with the driving-wheel in a manner similar to that now practised.

Having thus described my invention, what I claim as new, and desire to secure by Letters Patent, is—

1. I claim the construction of the oscillating valve T, and arrangement of the openings S P P', and R, substantially as shown and described.

2. I claim the arrangement of the piston-rods K and L, operating in one and the same end of the cylinder, substantially as shown and described.
